Application June 23, 1941, Serial No. 399,404

17 Claims. (Cl. 93—1)

This invention relates to the manufacture of handle attachments for paper shopping bags and the object is to provide an improved method and apparatus for the continuous production of handle attachments of the type comprising a substantially U-shaped handle forming string having its ends anchored to one side of a strain distributing strip which is adapted to be secured to the mouth portion of the bag.

An important feature of the invention resides in the manner in which the U-shaped handle forming strings are successively fabricated during intermittent movements of a continuous strain distributing strip and are successively stapled to said strip by stapling operations which are timed to occur when the strip is at rest.

Another feature of the invention resides in the manner in which each handle forming member, after being fabricated, is caused to advance with the strain distributing strip so that the side portions of the handle member are successively presented to a stapling head which is located at one side of the path of travel of the strip.

A further feature of the invention resides in the manner in which the intermittently advancing strip is cut transversely as it passes beyond the stapling station to provide a plurality of shorter strip sections each having one of the U-shaped handle forming members stapled thereto.

A further feature of the invention resides in the manner in which the shorter strip sections passing beyond the strip cutting station are engaged by passing-on means and delivered to an adhesive applying station where adhesive is applied to opposite sides of said strip sections to facilitate subsequent attachment thereof to the mouth portion of a bag.

A further feature of the invention resides in the provision of novel conveyor means to which the handle attachments are delivered from the gluing station and by means of which the handle attachments are conveyed to a handle applying station where the handle attachments are applied to the bags by manual labor or in any other desired manner.

The foregoing and other features and advantages of the invention will be more readily understood from the following detailed description taken in connection with the accompanying drawings, in which—

Figure 1 is a plan view showing, more or less diagrammatically, the general arrangement of the essential mechanisms embodied in our improved machine.

Figure 2 is a front elevation of the assembly shown in Fig. 1.

Figure 3 is a front elevation of the complete machine.

Figure 4 is a plan view of the machine shown in Fig. 3. In this view only certain elements of the stapling machine are indicated by dotted lines.

Figure 18 is a front elevation of the lifting device shown in Fig. 17.

Figure 19 is a detail view showing part of the shock absorbing connection provided between the handle forming element and its operating mechanism.

Figure 20 is a view of one of the handle attachments which our improved machine is designed to produce.

Referring to the diagrammatic illustrations appearing in Figs. 1 and 2, 5 designates a reel from which a narrow strip of cardboard 6 is drawn by feed rolls 7 which operate intermittently to move the strip along the upper surface of a table 8. As the strip 6 is moved past the handle forming station X a predetermined length of string 9 is fed across the upper surface of the strip from a reel 10 by means of intermittently operated string

feeding rolls 11. As the string 9 passes across the cardboard strip 6 it enters the downwardly opening substantially U-shaped channel 12 of a movable handle forming element 13. As the string is forced through the channel 12 it is bent in the form of a U-shaped handle loop 9a so that the free end of the string is again directed across the cardboard strip as indicated at 9b. When the end 9b of the string reaches the position shown in Fig. 1 it is automatically stapled to the underlying portion of the cardboard strip 6 by the operation of a stapling machine 15, the stapling head 16 of which projects over the upper surface of said strip. At about the same instant a string cutter 17a is operated to sever the end 9c of the handle loop 9a from the length of string coming from the feed rolls 11. As hereinafter explained, the stapling head 16 and the string cutter 17 operate at a time when the strip feeding rolls 7 and the string feeding rolls 11 are at rest so that the strip 6 is stationary during the aforesaid stapling operation.

When the stapling head 16 and the cutter 17 have completed the aforesaid stapling and cutting operations the string feeding rolls 11 remain at rest but the strip feed rolls 7 are again put into operation to advance the strip 6 a further predetermined distance along the table 8 and the handle forming element 13 is simultaneously moved in the same direction and to the same extent by a suitable reciprocating actuating bar 17 which is timed and operated as hereinafter described. The extent to which the strip 6 and the handle forming element 13 are moved simultaneously along the table 8 is predetermined so that the handle loop 9a is shifted to position X' to bring the end 9c beneath the stapling head 16. When this occurs the strip feeding rolls 7 are again brought to rest and the stapling head 16 is again operated to staple the end 9c of the handle loop 9a to the underlying portion of the strip 6. At the same time a strip cutter mechanism 19 is operated to cut the strip transversely at a predetermined point in advance of the leading end 9b of the handle loop 9a. When these second stapling and cutting operations have been completed the handle forming element 13 is lifted clear of the handle forming loop 9a and returned from the dotted line to the full line position shown in Fig. 1. At the same time the strip feed rolls 7 and the string feeding rolls 11 are caused to resume operation so that a further portion of the string 9 is fed across the strip 6 and into the channel of the handle forming element 13 to form a second handle loop which is subsequently stapled in place as described in connection with the first mentioned loop.

The handle forming element 13 is shown provided with a pin 20 which, as more fully described hereinafter, travels beneath a hinged lifting plate 21 as the handle former is advanced from the full to the dotted line position shown in Fig. 1. The plate 21 is pivoted at 22 to a bracket 23 projecting above the table 8 and is normally held against upward swinging movement by means of a spring 24. The right hand end of plate 21, as viewed in Fig. 1, is bent downwardly to provide the inclined portion 25. The hinged mounting of the plate 21 permits the inclined end 25 to be displaced upwardly to permit the pin 20 to pass from the full to the dotted line position shown in Fig. 1. The inclined portion 25 then drops down to a position opposite the pin 20 so that, during the return movement of the handle forming element 13 by the bar 17, the pin 20

rides up the inclined portion 25 and travels along the upper surface of the plate 21 until it passes beyond the left hand end of the plate and drops down to the starting or full line position shown in Fig. 1. As the pin 20 travels up the inclined portion 25 it lifts the channel portion 12 of the handle former 13 clear of the first formed handle loop 9a which is then in the dotted line position indicated at X'.

As the formation and stapling of the second handle loop is proceeding the first mentioned handle loop 9a is successively advanced to the positions indicated at X² and X³. When the first formed handle loop 9a has reached the position X³ the second formed handle loop 9a will be in the position indicated at X'. At this time the cutter mechanism 19 will be operating to cut the strip midway between the trailing end 9c of the first formed handle loop 9a which is at position X³ and the leading end 9b of the second formed handle loop 9a which is at position X'. The stapling head 16 will also be operating at this time to staple the trailing end 9c of the second formed handle loop 9a to the underlying portion of the strip 6. From this description it will be seen that successive operations of the cutter 19 are timed to divide the strip 6 into a plurality of small individual sections 6a each equipped with a handle loop 9a (see Fig. 20). Each of the successively separated handle carrying strip sections 6a is gradually moved along the table 8 by the intermittent advance of the main portion of the strip 6 until it is engaged by continuously rotating passing-on rolls 27 which serve to feed successive handle carrying sections 6a of the strip to suitable glue applying rolls 28. The machine is timed so that the gluing rolls 28 make one complete revolution in contact with each other before each handle section 6a which is being fed by the passing-on rolls 27 actually enters the nip between the gluing rolls. This enables the upper gluing roll 28 to be supplied with adhesive by contact with the lower gluing roll which operates in a glue containing tank 29. Each handle carrying section 6a of the strip is delivered by the gluing rolls 28 to an endless chain conveyor 31 so that the handle loops 9a are engaged by suitable carrying hooks 32 projecting laterally from the endless conveyor chain 33. In the present instance we have shown only the sprockets 34 around which the chain 33 is trained at the receiving end of the conveyor 31 but it will be understood that the chain 33 is also trained around similar sprockets at the discharge end of the conveyor. This chain conveyor serves to deliver the handle attachments to a station where said attachments are applied to the mouth portion of the bags by manual labor or in any other suitable manner.

In the foregoing description we have dealt with only the general arrangement and functions of the essential mechanisms embodied in our improved handle forming machine. Since the specific details of these mechanisms and the means provided for operating them in properly timed relation are subject to considerable variation in practice, it will be understood that the invention is not limited to those particular details which will now be described in connection with the complete mechanical assembly illustrated in Figs. 3 to 19 inclusive.

The strip feeding mechanism

The upper and lower feed rolls 7 of this mechanism are mounted on shafts 40 and 41 provided with intermeshing gears 42 and 43 (see Figs. 3,

4, 7 and 8). The lower shaft 41 carries a ratchet wheel 44 and a pinion 45, the former being fixed to said shaft and the latter being rotatably mounted thereon. The ratchet wheel 44 is driven by a pawl 46 pivoted to a pawl carrier 47 attached to the pinion 45. The pinion 45 is intermittently rotated in opposite directions by a rack member 48 having one end adjustably secured, by a slot and pin connection 49a, to a crank arm 49 carried by a crank shaft 50 mounted in the frame members 51 and 52. Crank shaft 50 is driven from the power shaft 53 of the machine through a gear train comprising gears 54, 55 and 56 (see Figs. 3 and 4). It will thus be seen that rotation of the crank shaft 50 serves, through the agency of the rack 48, pinion 45, pawl 46 and ratchet wheel 44, to effect intermittent rotation of the feed rolls 7 in a strip feeding direction whereby said strip is intermittently advanced a predetermined distance along the upper surface of the table 8 between successive operations of the stapling head 16, it being understood that the stapling operations are timed to occur when the rack member 48 is making a return or non-working stroke.

The string feeding mechanism

The upper and lower feed rolls 11 of this mechanism are carried by shafts 58 and 59 journaled in suitable frame members 60 and 61, said shafts being provided with intermeshing gears 62 and 63 (compare Figs. 4, 9, 10, 11 and 12). The lower shaft is driven through gears 65, 66, 67, 68 and 69 from a bevel gear shaft 70 which, in turn, is driven by bevel pinions 71 and 72 from an intermittently operated shaft 73. The last mentioned shaft (see Figs. 3, 9, 10 and 11) carries a ratchet wheel 74 and a pinion 75, the former being fixed to said shaft and the latter being rotatably mounted thereon. The ratchet wheel 74 is driven by a pawl 76 fixed to a pawl carrier 77 attached to the pinion 75 which is driven by a rack 78. One end of the rack 78 is adjustably secured, by a slot and pin connection 79, to a crank arm 80 carried by a crank arm shaft 81 journaled in the previously mentioned frame members 51 and 52 below the crank shaft 50. Shaft 81 is driven from shaft 50 by intermeshing gears 82 and 83. The construction and timing of this string feed mechanism is such that, at each operation thereof, a predetermined length of string is fed across the moving strip 6 and into the channel 12 of the handle forming element 13. This feeding of the string occurs when the handle forming element 13 is in the full line position shown in Fig. 1 and is discontinued during the previously mentioned stapling operations. In this connection it will be understood that the stapling operations take place during the return or non-working stroke of the rack 78.

The handle former and its operating mechanism

As shown in Figs. 15 and 16, the preferred embodiment of the handle forming element 13 comprises a plate 87 provided with an integral extension 87a at the entrance end of the channel 12. The side walls of the channel 12 are formed by inner and outer substantially U-shaped strips 88 and 89 whose upper edges are welded to the lower surface of the plate 87 as indicated at 90. The entrance end of the channel 12 is formed by end portions of the strips 88 and 89 which lie below and are welded to the plate extensions 87a. The exit end of the channel 12 is formed by the remaining end portions of the strips which pro-

ject beyond the edge 87b of plate 87 a distance substantially equal to the length of the extension 87a. Portions of the channel forming strips 88 and 89 which lie between the points Y (Fig. 15) and the exit end of the channel 12 are left free of attachment to the plate 87 so that these portions of the strips may be flexed to different positions of adjustment with respect to each other and with respect to the plate 87 to alter the contour of the channel to suit the characteristics of different types of strings which may be employed to provide the previously mentioned handle loops 9a. The free or flexible end portions of the channel forming strips 88 and 89 are provided with plate portions 90 and 91 equipped with fastening screws 92 working in slots 93 provided in plate 87. After the free ends of the channel forming strips have been flexed to the desired position of adjustment they are secured in place by tightening the screws 92 into clamping engagement with the upper surface of the plate 87.

The handle former 13 carries a plate 94 to which one end of the previously mentioned handle former operating bar 17 is bolted as shown to advantage in Figs. 3 and 4. The bar 17 works in a suitable guide 95 and has its opposite end secured to a suitable fitting 96 carried by one end of a pivot shaft 97 which extends transversely through the guide slot 98 of a suitable pivot guide 99. The other end of pivot shaft 97 is connected by a shock absorbing link 100 to the upper end of a cam operated lever 101 which is mounted to swing about an intermediate pivot shaft 102 and has its lower end disposed in riding engagement with an operating cam 103. As clearly shown in Figs. 3 and 19, the connection between the link 100 and the lever 101 comprises a fork member 104 whose arms 105 are pivotally secured to the upper end of lever 101 by means of a pivot bolt 106 which passes through the lever slot 107 and is fitted with a retaining nut 108. The link 100 extends slidably through the guide bore 109 of the fitting 104 and also through a slot 110 provided in a portion of the bolt 106 which lies between the fork arms 105. The free end of link 100 is fitted with stop nuts 111 which are engageable with the bolt 106 to limit movement of the link in one direction. A portion of link 100 is encircled by a shock absorbing spring 112 which is confined between the fitting 104 and a suitable abutment 104', the latter being fixed to said link. The lower end of lever 101 is held in contact with the cam 103 by a suitable spring 114 which is connected between said lever and a suitable anchoring bracket 115.

The lever operating cam 103 is fixed to one end of a shaft 117 the other end of which carries a gear 118 which is driven by a gear 119 on the previously mentioned cam shaft 50. As the cam 103 rotates it acts, through the lever 101, shock absorbing link 100, and bar 17, to shift the handle forming element 13 from the full to the dotted line position shown in Fig. 1, the return movement of the handle former being effected by the pull of the spring 114 as the lift portion of the cam 103 passes out of engagement with the lower end of lever 101. The handle former is stationary in the full line position shown in Figure 1 while the string 9 is being fed through the channel 12. It remains stationary until the leading end 9b of the loop 9a has been stapled to the underlying portion of the strip 6 by the stapling head 16. It then moves forward 75 with the strip 6 until the trailing end 9c of the

handle loop 9a lying within the channel 12 is brought beneath the stapling head 16. As soon as the last mentioned end 9c of the handle loop 9a lying within the channel 12 has been stapled in place the handle former is lifted clear of the handle loop 9a by the lifting plate 21 as the handle former commences its return movement to the starting position shown by full lines in Fig. 1.

The handle former lifting device

The preferred embodiment of this device is illustrated in Figs. 17 and 18. As here shown the plate portion 21 is provided with downwardly directed extensions 21a and 21b located adjacent opposite ends thereof. The extension 21a is pivotally secured to the upper portion of the bracket 23 by the pivot pin 22. The extension 21 serves as a stop which rests on the upper surface of the table 8 to limit downward movement of the inclined end 25 of plate 21. The spring 24 is coiled about the pivot 22 and has one end disposed to bear against a shelf portion 23a of the bracket 23. The remaining end of spring 24 is hooked over a pin 21c projecting outwardly from the extension 21b and normally serves to hold the plate 21 in the full line position shown in Fig. 18. During movement of the handle former 13 from the full to the dotted line position shown in Figs. 1 and 18 the pin 20 travels beneath the lower surface of the plate 21 which remains in its horizontal position until the pin 20 strikes the inclined portion 25 and lifts the plate 21 to the dotted line position shown in Fig. 18. When the handle former 13 comes to rest in the said dotted line position the pin 20 and the inclined portion 25 of the plate 21 are relatively arranged as shown in Figs. 1 and 18. Then, when the handle former 13 commences its return movement, the pin 20 rides up the inclined portion 25 and onto the upper surface of the plate 21 so that the handle former 13 is thus lifted clear of the handle loop 9a which previously occupied the channel 12. As the pin 20 travels beyond the left hand end of the plate 21, as viewed in Fig. 18, the handle former 13 drops down upon the table 8 in position to receive the leading end of a second length of string 9 which is then fed into the channel 12 to form a second handle loop.

The string cutting mechanism

As indicated in Fig. 4, the string 9 is led to the nip of the string feeding rolls 11 through suitably supported guide bushings 122 and 123. From the rolls 11 the string passes through a further guide bushing 124 and over the knife 17a and the upper surface of the strip 6 into the channel 12 of the handle forming element 13. As shown more particularly in Figs. 11 and 12 the string cutter 17a works against one end face of the bushing 124. The cutter 17a is provided, at its upper end, with a V-shaped cutting edge 17b which serves to sever the string close to the bushing 124 during upward movement of the cutter. The cutter 17a is fastened to a slide 126 by bolts 127 working in a slot 128 provided in a frame member 129. The slide 126 and the attached cutter 17a are periodically raised to a string cutting position by a slide operating cam 126a fixed to one end of a shaft 130. The other end of shaft 130 carries a gear 131 which is driven through an idler gear 132 from a gear 133 mounted on a cam shaft 134 which also controls the operation of the stapling head 16, as hereinafter described. As indicated in Figs. 3 and 4, the cam shaft 134 is driven from the power shaft 53 through a gear

train comprising gears 136, 137, 138 and 139. By the driving mechanism herein described the operation of the cutter 17a is timed so that the cutter makes a working stroke each time the string feeding rollers 11 are brought to rest after feeding a predetermined length of string into the channel 12 of the handle forming element 13.

The stapling machine timing mechanism

10 In the present instance we have shown a conventional stapling machine 15 which is known to the trade as the "Ideal Double Head Stitching Machine." This type of stapling machine is characterized by the fact that the stapling head 16 drives two parallel staples at each operation thereof. We prefer to use this type of stapling machine since it enables each of the two arms of the handle loop 9a to be fastened to the underlying strip 6 by two staples S, as shown to advantage in Fig. 1. It would, of course, be feasible to use a single head "Ideal Stitcher" or other make of stapling machine which drives only a single staple at each operation of the stapling head 16.

25 The stapling machine 15 is provided with a driving pulley A' adapted to be belt connected to a driving motor or other suitable driving member (not shown). The pulley A' drives the stapling machine through a conventional clutch 30 B the engagement and disengagement of which is controlled by the operation of a vertically movable clutch controlling rod C. The rod C is normally held in a raised clutch disengaging position by suitable spring means (not shown) and is 35 periodically moved downwardly to a clutch engaging position by means of a cam 143 which is carried by the previously mentioned cam shaft 134. The cam 143 acts against a roller 144 (Fig. 5) at the lower end of rod C and this controls 40 the periodic operation of the stapling head 16 in suitably timed relation to the other mechanisms previously described.

The strip cutting mechanism

45 This mechanism is shown in detail in Figs. 3, 4, 13 and 14. It comprises an upper stationary knife 146 and a lower movable knife 147, both of which extend transversely across the path of travel of the strip 6 along the table 8. The stationary knife 146 is carried by a suitable bracket structure 148 which also carries a yieldingly mounted presser foot 149 beneath which the strip 6 travels as it passes toward the cutting knives 146 and 147. The purpose of the presser foot 149 is to guide the strip 6 under the upper stationary knife 146 and also to hold down the handle loop 9a when the handle forming element 13 is coming into its lifting position before returning to full line position shown in Fig. 1. The presser foot 149 is carried by vertical guide rods 150 which slide vertically through suitable guide openings provided in the bracket structure 148 and which are normally held in their lowermost position by suitable biasing springs 151. The movable cutting knife 147 normally lies below a slot 153 provided in the table 8 and is pivoted at one end to a suitable bracket 154. The other end of knife 147 rests on one end of a lever 155 the other end of which is pivoted to a frame portion of the 60 machine as indicated at 156. Lever 155 is held in riding engagement with an operating cam 157 by means of a spring 158 which is connected between the free end of the movable knife 147 and a suitable anchoring member 159. At each operation of the cam 157 the movable knife 147 is 65 70 75

raised by the lever 155 and cooperates with the stationary knife 146 to sever the strip 6 transversely across its entire width. The cam 157 is fixed to a cam shaft 160 which is driven from the previously mentioned cam shaft 134 through a gear train comprising gears 161, 162 and 163.

The passing-on rolls and their operating mechanism

The passing-on rolls 27 are fixed to upper and lower shafts 165 and 166 suitably journaled in the frame structure of the machine. Shaft 165 carries a gear 167 (Fig. 4) which drives another gear (not shown) fixed to shaft 166. Shaft 165 is driven from the shaft 160 of the strip cutter mechanism 19 by a gear train comprising gears 168, 169 and 170. The periphery of the upper passing-on roll 27 is shaped to provide recessed portions 172 which enable the roll to suitably accommodate the handle loops 9a as the roll is performing its function of passing the handle attachments onto the gluing rolls 28. The lower passing-on roll 27 is a relatively small roll which is preferably provided with a knurled peripheral surface for engagement with the bottom of the strip portion of the handle attachment passing thereover.

The gluing rolls and operating mechanism

The gluing rolls 28 are mounted on upper and lower shafts 175 and 176 so that the peripheries of these rolls are in contact with each other except when a handle attachment is passing therebetween. The upper gluing roll shaft 175 is driven from the upper advancing roll shaft 165 through a train of gearing comprising gears 179, 180 and 181. The upper gluing roll 28 is provided with notches 28a in which the sides of the handle loops 9a are accommodated as each handle attachment is passed between the gluing rolls and onto the conveyor 31.

Glue is supplied to the tank 29 from an inverted bottle-shaped container 29a which is supported in an upright position by a suitable frame structure 29b, the flow of glue from the container 29a to the tank 29 being such as to maintain the glue at a substantially constant level in said tank.

The conveyor operating mechanism

The sprockets 34 of the conveyor 31 are shown mounted on upper and lower shafts 184 and 185 suitably journaled in frame portions of the machine. The upper shaft 184 is driven from the upper gluing roll shaft 175 by a gear train comprising gears 186, 187 and 188.

The handle attachments are delivered from the gluing roll to the conveyor 31 in such manner that, as the handle attachments pass clear from the gluing rolls and tend to fall to a vertical position, the handle loops 9a are caught and suspended by the conveyor hooks 32.

The power shaft driving mechanism

The main power shaft 53 is fitted, at one end, with a hand wheel 191 and at the other end with a fixed pulley 192 and a loose pulley 193. When the machine is at rest the driving belt 194 (Fig. 6) is trained around the loose pulley 193 and a driving pulley 195 carried by a driving shaft 196. Both runs of the belt 194 pass through a belt shifter 197 provided at one end of a belt shifting rod 198 which extends transversely across the frame of the machine and is provided, at its opposite end, with a downwardly directed

handle member 199. The belt 194, belt shifter 197, and belt shifting rod 198 are normally held in the full line position shown in Fig. 6 by a biasing spring 201, one end of said spring being anchored to the machine frame as indicated at 202 and the other end being anchored to a post 203 projecting upwardly from the belt shifting rod 198. When it is desired to establish a drive connection between the power shaft 53 of the machine and the driving pulley 195 the handle 199 of the belt shifting rod 198 is pulled to the left to the dotted line position shown in Fig. 6 so that the belt 194 is thus shifted from the loose pulley 193 onto the fixed pulley 192. The handle member 199 of the belt shifter is retained in the dotted line position shown in Fig. 5 by means of a latch rod 204. This rod 204 is slidably mounted in suitable bearing brackets 205 so that one end thereof may be inserted in an opening 206 provided in the clutch shifting handle 199 when the latter is in the dotted line position shown in Fig. 6. When it is desired to disrupt the drive connection between the pulleys 192 and 193 this is accomplished by pulling the latch 204 to the right as viewed in Fig. 3 so that the left hand end of the rod is withdrawn from the opening 206 of the clutch shifting handle 199. This release of handle 199 permits the spring 201 to move the clutch shifting rod 198 to the right as viewed in Fig. 6 so that the belt is thus shifted from the fixed pulley 192 back onto the loose pulley 193 which revolves freely on the shaft 53.

Having thus described the operating principles of our invention and the preferred mechanical embodiment thereof it will be understood that various modifications in the construction and assembly of the component parts may be resorted to within the scope and spirit of the invention as defined by the appended claims.

Having thus described our invention, what we claim is:

1. Apparatus for the continuous production of handle attachments of the character described comprising a handle forming member provided with a substantially U-shaped handle forming channel, means for intermittently advancing a continuous strip along a predetermined path of travel toward which the ends of said channel are directed, means for feeding a predetermined length of string across said strip and into said channel whereby said length of string is bent to provide a U-shaped handle having portions of its side arms extending across said strip and means for stapling said portions of the side arms of the U-shaped handle to said strip.

2. Apparatus for the continuous production of handle attachments of the character described comprising means for intermittently advancing a continuous strip along a predetermined path of travel, a movable handle former located at one side of said path and provided with a substantially U-shaped handle forming channel the ends of which are directed toward said path, means located at the opposite side of said path for feeding a predetermined length of string across said strip and through the channel of the handle former whereby said length of string is bent to provide a U-shaped handle having portions of its side arms overlying said strip, means functioning, upon completion of said handle, to staple the leading side of the handle to the underlying portion of the strip, said string feeding means being arranged to operate at a time when said strip is moving relatively to said handle former and being

brought to rest when the formation of the handle is completed, said stapling means being arranged to operate when the strip is brought to rest following the formation of said U-shaped handle, said apparatus being further characterized in that the strip, the U-shaped handle and the handle former are moved as a unit to bring the trailing side of the handle into operative relation with the stapling means following the aforesaid stapling of the leading side of the handle to said strip and means whereby a further operation of the stapling means is effected to staple the trailing side of the handle member to said strip following the aforesaid unitary movement of the strip, handle member and handle former.

3. Apparatus for the continuous production of handle attachments of the character described comprising means for intermittently moving a continuous strip past a plurality of stations including a handle forming station, a handle stapling station and a strip cutting station, a plurality of handle forming means located at the handle forming station including means for feeding a predetermined length of string across said strip, means for forming said length of string into a U-shaped handle having portions of its side arms overlying said strip and means for severing said length of string from the remainder of the string when the formation of the U-shaped handle is completed, intermittently operated stapling means located at said handle stapling station and functioning to staple the leading and trailing sides of the U-shaped handle to said strip by successive stapling operations which are timed to coincide with predetermined interruptions of the advancing movement of the strip, and intermittently operated strip cutting means located at said strip cutting station, said strip cutting means functioning to cut said strip into shorter sections by successive cutting operations which are timed to occur when the strip is at rest, the intervals between successive operations of the cutting means being timed with relation to advancing movements of the strip so that each of the shorter sections into which the strip is divided by the strip cutting means will include a previously applied U-shaped handle.

4. Apparatus as set forth in claim 3 including means whereby the shorter strip sections which are separated from the main strip by the strip cutting means are passed from said cutting means to a gluing station and a conveyor to which the finished handle attachments coming from the gluing station are delivered.

5. In apparatus of the character described the combination of a table, a handle former provided with a downwardly opening handle forming channel facing the upper surface of the table, means for moving the handle former along the upper surface of the table from a starting position to an advanced position and then returning the handle former to said starting position and means for lifting the handle former to an elevated position above the upper surface of the table as the handle former commences its return movement, said lifting means serving to retain the handle former in its elevated position until the handle former has completed a predetermined portion of its return movement.

6. Apparatus as set forth in claim 5, in which the means for moving the handle former is designed to permit the latter to remain stationary for a predetermined interval as it reaches the end of its travel in either direction.

7. Apparatus as set forth in claim 5, in which the means for moving the handle former com-

prises a lever, means including a cam for imparting swinging movement to said lever and means connecting said lever to said handle former.

5. 8. Apparatus as set forth in claim 5, in which the means for moving the handle former comprises a lever, means including a cam for imparting swinging movement to said lever and a shock absorbing connection through which the 10 swinging motion of the lever is transmitted to said handle former to reciprocate the latter.

9. Apparatus as set forth in claim 5, in which the means for moving the handle former comprises an intermediately pivoted lever, a cam, a 15 biasing spring arranged to hold one end of said lever in contact with said cam and means connecting the other end of the lever to said handle former to reciprocate the latter in response to swinging movement of the lever.

20 10. Apparatus as set forth in claim 5, in which the handle former comprises a horizontal plate and a pair of horizontally arranged U-shaped strips arranged one within the other in spaced relation and having upper edge portions thereof 25 secured to the underside of said plate, said strips forming the inner and outer side walls of said handle forming channel.

11. Apparatus as set forth in claim 5, in which the means for lifting the handle former comprises a lifting plate mounted on said table and a projection from the handle former adapted to ride upon the upper surface of said plate and to thereby elevate the handle former during a portion of its return movement.

35 12. Apparatus as set forth in claim 5, in which the means for raising the handle former comprises a projection extending outwardly from said handle former and a lifting plate arranged on the table so that said projection travels beneath 40 said plate during the advancing movement of the handle former and is caused to travel in an elevated path along the upper surface of said plate during a portion of the return movement of the handle former.

45 13. Apparatus as set forth in claim 5, in which the means for lifting the handle former comprises a pivotally mounted lifting plate arranged with the body portion thereof spaced above the upper surface of said table and with one end 50 thereof extending downwardly toward said table and a projection from the handle former adapted, during the advancing movement of the handle former, to travel beneath the body portion of said plate and to engage and lift the downwardly 55 directed end of said plate as it passes therebeyond, the arrangement being such that said projection is caused to ride the upper surface of said plate during the return movement of said handle former.

60 14. A handle former of the character described comprising a plate, horizontally arranged U-shaped strips having upper edge portions thereof secured to the underside of said plate, said strips being arranged one within the other and spaced apart to provide the side walls of a substantially U-shaped handle forming channel; corresponding end portions of said strips being free of attachment to said plate and being adjustable toward or away from each other and means for securing said flexible end portions of the strips in adjusted position.

70 15. A handle former of the character described comprising a plate, horizontally arranged U-shaped strips having upper edge portions thereof 75 secured to the underside of said plate, said strips

being arranged one within the other and spaced apart to provide the side walls of a handle forming channel, corresponding end portions of said strips being free of attachment to said plate and being sufficiently flexible to permit them to be adjusted toward or away from each other and means for securing said flexible end portions in adjusted position comprising clamping screws passing through slots provided in said plate and having screw threaded engagement with the said flexible end portions of the strips.

16. In apparatus of the character described, the combination of a table, a handle former movable over said table from a starting or handle forming position to an advanced or handle shifting position and vice versa, said handle former being provided with a downwardly opening and substantially U-shaped handle forming channel facing the upper surface of the table, the ends of said channel being directed toward one side of the path of movement of said handle former, means for reciprocating said handle former whereby the latter is shifted from its starting to its advanced position and vice versa, means for lifting the handle former to an elevated position with reference to the upper surface of the table as the handle former commences its return movement after being shifted to its advanced position, said lifting means serving to retain the handle former in its elevated position until the handle former has completed a predetermined portion of said return movement, means for intermittently advancing a strip of material along a predetermined path of travel toward which the

5 ends of said handle forming channel are directed, means functioning when the handle former is in its starting or handle forming position to feed a predetermined length of string across said strip and into said handle forming channel whereby said length of string is bent to provide a U-shaped handle having portions of its side arms extending across said strip, stapling means, means functioning upon completion of said handle to operate said stapling means to staple the leading side of the handle to said strip, and means for effecting a further operation of said stapling means to staple the trailing side of the handle to said strip when the handle former is shifted to its advanced position, the arrangement being such that the handle contained within the handle forming channel of the handle former is caused to advance with said handle former but is disengaged by the handle member as the latter is elevated with reference to the table during the return movement thereof.

10 15 20 25 30 17. Apparatus as set forth in claim 16 including means whereby the string feeding means is caused to operate when the handle former is in its handle forming position, is caused to cease operation during the period that the handle former is being moved to its advance position and then returned to its handle forming position and is caused to resume operation as soon as the handle former is returned to its handle forming position after each advance thereof.
